UNITED STATES PATENT OFFICE.

JOSEPH HAYDEN CROSBY, JR., OF JACKSONVILLE, FLORIDA.

DESIGN FOR A KNIFE-HANDLE, &c.

SPECIFICATION forming part of Design No. 22,681, dated August 8, 1893.

Application filed July 5, 1893. Serial No. 479,658. Term of patent 7 years.

To all whom it may concern:

Be it known that I, JOSEPH HAYDEN CROSBY, Jr., of Jacksonville, in the county of Duval and State of Florida, have invented and produced a new and original Design for Handles of Knives and Like Articles, of which the following is a specification, reference being had to the accompanying drawing, which illustrates the same.

10 The general outline form of the handle is of the pandurate order, the sections of the same being bounded by a plain beading A, and separated by a ribbon B.

The lower end of the handle terminates in 15 the armorial shield C which bears a coat of arms D. The upper portion of the handle is fashioned into the form of the induplicate volutes E, which join the shank F of the blade

G or other part to which the handles may be attached. This blade or part G does not, 20 however, form any portion of the design. The face of the handle is stippled, and bears the representation of oranges H, orange blossoms I, and orange leaves J, these representations being arranged along the medial line of the 25 face of the handle and decreasing in size toward the upper part in conformity with the incurving outline thereof.

What I claim is—

The design for handles of knives and similar articles, substantially as herein shown and described.

JOSEPH HAYDEN CROSBY, JR.
